Inventor

Edward J. Widmer.

By *A. J. O'Brien*

Attorney

UNITED STATES PATENT OFFICE.

EDWARD J. WIDMER, OF DENVER, COLORADO.

CHISEL HANDLE.

Application filed September 1, 1925. Serial No. 53,772.

To all whom it may concern:

Be it known that I, EDWARD J. WIDMER, a citizen of the United States, residing at the city and county of Denver and State of Colorado, have invented certain new and useful Improvements in Chisel Handles; and I do declare the following to be a full, clear, and exact description of the invention, such as will enable others skilled in the art to which it appertains to make and use the same, reference being had to the accompanying drawings, and to the characters of reference marked thereon, which form a part of this application.

This invention relates to improvements in chisel handles.

A carpenter's chisel is a tool that is often-times employed in such a way that the end of the handle must be struck by a hammer. As the handle is almost invariably made from wood it readily splits and becomes useless. To prevent this splitting, it is customary to secure to the end of the handle one or more layers of leather, preferably sole leather. It has been found from experience that leather will not stand up under repeated hammerings, but will lose its resiliency and become flabby. When this occurs the handle will split and become useless.

I have found that if I substitute for leather a material composed of highly compressed spinnable textile fibers that are held together by means of a phenolic condensation product or synthetic resin, such as bakelite, that better results are obtained than with the leather. The fibrous material treated in the manner suggested is unaffected by moisture and stands up under constant hammering much better than leather. It is also somewhat resilient and will not stretch to any appreciable extent.

In order more clearly to describe my invention I shall have reference to the accompanying drawing in which the same has been illustrated in its preferred form and in which:

Fig. 1 shows a view of a carpenter's chisel provided with my improved handle, a portion of the protective end member being

broken away to show the manner of securing the same to the handle;

Fig. 2 is an end view of the handle shown in Fig. 1, and

Fig. 3 is a section taken on line 3—3 Fig. 1. Numeral 1 indicates an ordinary carpenter's chisel having a socket 2 into which the handle 3 is fitted. The outer end of the handle has an axial cylindrical lug 4 which projects through an opening in the fibrous protector member 5. The function of the lug 4 is merely to hold the member 5 in place and it may therefore be of comparatively small diameter and should fit tightly in the opening of member 5. When a hammer is employed for striking the end of the handle, the force of the blow will be received by the end face of member 5 and transmitted evenly to the shoulder 6 of the handle 3. Owing to the fact that member 5 is resilient and hard, it forms an almost perfect protector for the handle. Member 5 is constructed of superposed layers of canvas which is first impregnated with a phenolic condensation product such as bakelite; the parts are then highly compressed and subjected to sufficient heat to harden the bakelite. Such an article is waterproof, resilient and tough and besides this it holds its form and does not stretch or get out of shape.

Having now described my invention what I claim as new is:

1. A chisel handle having secured to one end a protective member formed of highly compressed fibrous material impregnated with a phenolic condensation product that has been hardened.

2. A chisel handle having secured to one end a protective member formed from a plurality of layers of canvas that has been impregnated with a phenolic condensation product and compressed.

3. A chisel handle having secured to its end a protector consisting of highly compressed canvas cemented together by means of a phenolic condensation product.

In testimony whereof I affix my signature.

EDWARD J. WIDMER.
